UNITED STATES PATENT OFFICE.

FRANK TEMPEST STARE, OF WAUKESHA, WISCONSIN, ASSIGNOR TO AMERICAN
DEHYDRATING COMPANY, A CORPORATION OF WISCONSIN.

AIR-DRIER.

No. 872,027.

Specification of Letters Patent.

Patented Nov. 26, 1907.

Application filed May 27, 1907. Serial No. 375,864.

To all whom it may concern:

Be it known that I, FRANK TEMPEST STARE, a citizen of the United States, residing at Waukesha, in the county of Waukesha 5 and State of Wisconsin, have invented certain new and useful Improvements in Air-Driers, of which the following is a specification.

My invention relates to apparatus used in 10 extracting moisture from air or other vapor, and consists in the construction and arrangement of a series of receptacles adapted to contain moisture-absorbing substance, through which receptacles the air to be dried, is forced 15 to pass.

Heretofore it has been the custom, as far as I am aware, to support the moisture-absorbing substance, used in air-driers, and the like, upon shallow iron trays or pans, supported one above another in a chamber, or else 20 to place the moisture-absorbing substance upon screens or gratings supported by the walls of the chamber.

The object of my present invention is to 25 provide a cup or receptacle for the moisture-absorbing substance, and to so arrange and support a plurality of layers of such cups or receptacles that all the air to be dried is forced to come into contact with a large 30 amount of the moisture-absorbing substance during its passage downwardly through the drier.

The construction of the cups and the arrangement of the same to form the drier will 35 be best understood from the following detailed description, taken in connection with the accompanying two sheets of drawings, in which

Figure 1, is a vertical section through an 40 air drier constructed according to my invention. Fig. 2, is a horizontal section through the same taken on three different levels. Fig. 3, is an enlarged side view of a portion of the stack of cups or receptacles, constituting the air drier, and Fig. 4, is a plan view of Fig. 3.

In these views 1 represents the walls of the inclosing casing of the drier, the same being closed at the top, at 2, with the exception of 45 an opening for the stack 3, which will be referred to further on.

The cups or receptacles 4, which contain a moisture-absorbing substance, such as calcium chlorid, for example, and the detailed

construction of which will be described here- 55 inafter, are arranged in superimposed layers within the casing, the lowest layer being supported on a parallel series of channel bars 5, running transversely of the drier. The cups of each layer are arranged as shown in Fig. 4, 60 the cups of one layer standing above and below the spaces between the cups of the adjacent layers. Between each layer is placed a perforated metal plate 6, the openings 9 in which lie over the open ends of the cups in 65 the layer beneath.

The construction of the cups will now be 70 described in detail and, as they are identical in form, a description of one of them will suffice.

As shown in the drawings, the cups are circular in cross section but, while this is a convenient form for the purpose of manufacture, it is not essential that the cups be circular. They may be square, or of any other 75 convenient shape, it being only necessary that they be identical in shape and size. However, as I have stated, I prefer to use circular cups, which are drawn up from sheet steel, a small flange 10 being formed around 80 their open end; a slight distance below the flange, at diametrically opposite points four apertures 8 are formed in the walls of the cup.

The openings 9 in the plate 6, above referred to, are smaller in diameter than the 85 cups, and are spaced to lie concentrically with the cups of the layer below. In said openings 9 are supported open-ended tubes 12 which project downwardly into the corresponding cups to a point somewhat below 90 the level of the apertures 8, in the walls of the cup. The function of these tubes is to direct the air coming through the openings in the plate downwardly toward the bottom of the cups so as to bring the air into contact 95 with the chlorid and prevent its direct escape through the side openings of the cups. The use of these tubular guides is not absolutely necessary but it results in a more complete dehydration of the air, and therefore, I 100 prefer to employ them. Of course, these guides need not be cylindrical, but may taper upwardly or downwardly, if desired.

Within the casing of the drier, above the plate covering the top layer of cups is an inlet opening 15, through which the air to be dried enters, and below the channel-irons 5 is an outlet opening 16 for said air. It will be

seen that in its passage downwardly from the inlet 15 to the outlet 16, the air first enters the cups of the top layer through the openings in the plate above the same and 5 passing through the tubular guides comes into contact with the chlorid contained in said cups and then passes upwardly and out through the openings 8 in the walls of said cups into the spaces between each four cups 10 of said layer, from which it passes downwardly through the openings in the plate next below and thence into the cups of the layers below said plates and so on.

After the air to be dried has been passed 15 through the drier for a certain time, the chlorid becomes too moist for efficient operation, and consequently, the flow of air is cut off, and hot air is passed upwardly through the stack of cups, from which it removes the 20 moisture collected. This hot air enters the bottom of the drier through the inlet 17 and escapes through the stack 3 at the top of the drier.

The inlet and outlet pipes are provided 25 with valves 19, to control the operation of the drier.

Having thus described my invention, what I claim is:

1. An air drier, comprising a superimposed 30 series of layers of receptacles for moisture-absorbing substances, the receptacles of each layer lying over the spaces between the receptacles of the layer below, each receptacle being open at the top and having openings in 35 its side walls and a perforated plate interposed between each pair of layers, the openings in said plates lying over the open ends of the receptacles of the layer beneath.

2. An air drier comprising a casing pro- 40 vided with an apertured floor, a series of superimposed layers of cups or receptacles

supported on said floor, and a perforated plate interposed between each two layers.

3. An air drier comprising a casing provided with air inlets and outlets at its top and bottom and with an apertured floor, superimposed series of layers of cups supported on said floor, the cups of each layer being staggered relatively to the cups of the adjacent layers, and a perforated plate interposed between each pair of layers. 50

4. An air drier, comprising a series of superimposed layers of cups for moisture-absorbing material, the cups of one layer lying over the spaces between the cups of the 55 layer below, a perforated plate interposed between each two layers of cups and tubular funnels supported by said plates and projecting downwardly into said cups.

5. An air drier comprising a series of superimposed layers of cups having openings in their side walls, the cups of each layer lying over the spaces between the cups of the 60 layer below, a perforated plate interposed between each two layers and a tubular funnel supported in the openings of said plates, and projecting downwardly into said cups 65 below the level of said openings in their walls.

6. In an air drier, a receptacle for moisture-absorbing substance, consisting of a cup having diametrically opposite openings in its walls and a tubular guide or funnel supported above said cup and projecting downwardly therein to a point below the 70 level of said openings.

In testimony whereof I have affixed my signature, in presence of two witnesses.

FRANK TEMPEST STARE.
